By James T. Parkleau,
his attorney.

UNITED STATES PATENT OFFICE.

LLOYD BROWN, OF SHERMAN, CALIFORNIA, ASSIGNOR, BY MESNE ASSIGNMENTS, TO C. B. HURTT, W. F. PETERSON, GEORGE BAYNE STEPHENS, AND CATHERINE BAYNE STEPHENS, ALL OF LOS ANGELES, CALIFORNIA, AND G. A. STEPHENS, OF MOLINE, ILLINOIS, TRUSTEES.

THEATER.

Application filed July 25, 1922. Serial No. 577,475.

To all whom it may concern:

Be it known that I, LLOYD BROWN, a citizen of the United States, residing in Sherman, county of Los Angeles, State of California, have invented new and useful Improvements in Theaters, of which the following is a specification.

This invention relates to theater structures generally; and one of the objects of the invention is to provide a novel and useful design and structure that will provide a maximum utilization of space and will furthermore afford facilities for attaining continuity of action; that will afford conveniences for the setting of stages, etc. There are many other objects and corresponding accomplishments of the invention; but all will be best understood, and the invention itself will be best understood, from the detailed description of a preferred and specific form of theater structure that embodies the invention. After I have given such detailed description, the salient features of the design and structure will then be easily seen.

For the purposes of the following detailed description I refer now to the accompanying drawings in which—

Fig. 1 is a floor plan of my improved theater structure; Fig. 2 is a transverse vertical section of the theater structure taken on line 2—2 of Fig. 1, but showing only the lower parts of the structure; Fig. 3 is a vertical section taken as indicated by line 3—3 on Fig. 1; Fig. 4 is a vertical section taken as indicated by line 4—4 on Fig. 1; Fig. 5 is a fragmentary section taken as indicated on line 5—5 of Fig. 1; and Fig. 6 is a plan section on line 6—6 of Fig. 3.

Fig. 1 shows a plan at the street level. At the street level there is a main entrance lobby 10, from which a stair 11 leads down to a platform 12 and then further stairs 13 lead down to the level of the foyer floor 14. The foyer is on a level below the street level. It is indicated F in the drawings. The entrances to the foyer are at 14 from the stairs 13, and the coupon or ticket office 15 is located beneath and between the stairs as is clearly shown in the drawings, the ticket office opening out into the foyer. In planning my theater for a square or rectangular plot of ground, the exterior configuration of the foyer will probably be square, and I have so shown it in the drawings; but it of course

can be made of any other suitable exterior configuration. At the several sides of the foyer, preferably against the exterior walls, there are inclines 20 that lead up to the floors 21 of the various auditoriums; these inclines emerging into the auditoriums near their back corners, as is best shown in Fig. 1.

One of the features of my invention is that I have a plurality of separate and distinct auditoriums arranged around a common central stage. In the particular case I show the square or rectangular theater structure divided into four auditoriums A¹, A², A³, and A⁴, arranged around the common central stage S. This stage is preferably circular and revolving and also vertically movable. It may preferably be constructed somewhat in the manner as indicated in the drawings, and be supported on a central plunger P whose lower end extends into a well 1. The machinery room M may be located below the stage around its central support; and any suitable machinery may be used (it is not necessary to illustrate it in these drawings) to raise and lower the stage by the well known hydraulic action; and also to revolve it from time to time, as may be required. When the stage is in use it occupies a position shown in full lines in Fig. 3; when it is being set preparatory to a performance, it is lowered to the position shown in dotted lines at S² in Fig. 3. In its last mentioned position it is then on a level with floor 25 of the work and storage rooms W, which rooms immediately surround the stage space and open directly into the stage space as is indicated in the drawings. Immediately surrounding the rooms W, there may be a circularly arranged series of dressing rooms R; and the foyer F extends completely around the circular exterior wall of these dressing rooms R. The working and dressing rooms, etc., the space where the stage is set, are thus all excluded entirely from the foyer; but the foyer, extending completely around the whole structure, affords entrance to any one of the auditoriums.

Around the central stage space there is a circular wall 30 that extends from the auditorium floors preferably to the roof of the structure; and in this circular wall four stage proscenium openings 31 are provided at the auditorium level. (Of course, when

I say that the auditoriums and the proscenium openings are on or at the same level. I do not mean to say that they are exactly level with each other, but use this phraseology to distinguish generally between the general level of the auditoriums and that of the rooms, etc., below. As a matter of fact the auditorium floors are, at their fronts at least, below the proscenium openings, as illustrated). In front of each proscenium opening there is provided the orchestra pit 32; and the usual foot-light trough 33 is provided at the stage level. The stage itself carries four removable walls 35 which may be placed on the stage in such a manner, as indicated in Fig. 1, as to divide the whole revolving stage S into four individual stages, one facing each auditorium. These individual stages may of course be used for any kind of show or entertainment; they may be set for a drama or the like; or a motion picture screen 36 may be set on them or let down from above the stage. Above the stage there may be provided a revolving grid as indicated at 40 for the purposes of handling scenery, etc. upon the stage; and the pin-rail balconies 41 are suspended from this revolving grid. These galleries may be swung around to any position and thus to positions in front of the spaces above stage entrances 42, in which spaces there may be storage, etc., floors 42^a (see Fig. 3) at the level of the balconies; and also floors at other levels, as at 42^b. The floors of these stage entrances 42 are located at the auditorium level, that is substantially at the level of the stage S when in its position shown in full lines in Fig. 3. From these stage entrances 42 exit passages 43 lead out to the exterior walls of the building, as illustrated, and the walls of these exit passages form the dividing partitions between the four auditoriums. These walls may be provided with exit doors 44 leading from the several auditoriums into the exit passages 43. Thus the exit passages 43 serve a double purpose; they serve to provide additional exits from the several auditoriums (additional to the direct exits at 45) and they also serve as communications directly between the stage and the street exits or entrances at 46. Thus they may be convenient in many instances in bringing in or removing scenery, etc., to and from the stage, and one, or more, of these entrances may also serve for communication between the street and the work rooms. For instance at 60 in an entrance 43 there may be a hinged runway that may be let down to the work room floor or raised to form a continuation of the floor of passageway 43. If it is so desired, the division walls 35 may be removed from the stage and the stage used as a single whole for all four auditoriums at once. This may be particularly desirable for some forms of entertainments.

On the other hand for vaudeville entertainment, motion picture shows, etc., the stage may be divided as illustrated; the various separate stage areas set while the stage is in its lowered position, the stage raised to its 70 position at the auditorium level, and then, by revolving the stage from time to time, different settings and different entertainments may be brought before the several audiences. All this may be done and an entertainment 75 carried on without the necessity of taking any time for changing scenery. It will be noted that one set of general stage paraphernalia will suffice practically as well for all four separate stages as for a single stage. I wish further to point out that the stage 80 may be raised above the level shown at S, to elevate scenery for certain scenic purposes. The revolving grid and galleries also 85 allow the scenery to be revolved either with the stage or, for instance, for transformation purposes, oppositely to the stage.

The arrangement that I have described lends itself very readily to economical stage 90 operations, stage setting, etc. When the stage is lowered into the work room it is freely and easily accessible from all sides. More space is available for the work room than is ordinarily the case, because in my arrangement the work is not limited as in the usual theater by the fact that the auditorium faces the stage at one side. When the stage is in its lowered position the work room entirely surrounds it. Likewise, when the stage 95 is set and a show is being produced, certain present limitations are avoided, and the stage space may be much more economically and efficiently used, because it is then entirely surrounded by auditoriums. And this is attained without losing any convenience or effectiveness of stage entrances and exits.

Furthermore in my arrangement, although I provide an ample and effective foyer that leads easily and directly to all the auditoriums, I do not have to give up any street 110 level space to it. The street level space is most effectively used for auditorium purposes.

Having described a preferred form of my invention, I claim:

1. A theater structure that involves a central vertically movable stage, auditoriums surrounding said central stage at one level, and working rooms surrounding the central stage at another level, a foyer at a level below the auditorium level and extending around the work rooms, an entrance to the foyer, and communications between the foyer and the auditoriums.

2. A theater structure that embodies a central stage enclosing wall with a plurality of proscenium openings through it, a vertically movable stage located within the circular wall, said stage being movable from the level of the proscenium openings to an-

- other level; a plurality of separated auditoriums collectively surrounding the stage at the level of the proscenium openings, and working rooms surrounding the stage at said other level; an entrance foyer substantially at the level of the working rooms, and entirely surrounding the working rooms, and communications between said entrance foyer and the several auditoriums. 5
- 10 3. A theater structure that embodies a central wall with a plurality of proscenium openings through it, a stage enclosed by said wall, a plurality of auditoriums facing said central stage, an auditorium at each proscenium opening, and walled passage-ways leading between the several auditoriums to the stage, providing stage entrances and providing division walls between the several auditoriums. 15
- 20 4. A theater structure that embodies a central wall with a plurality of proscenium openings through it, a stage enclosed by said wall, a plurality of auditoriums facing said central stage, an auditorium at each proscenium opening, and walled passage-ways leading between the several auditoriums to the stage, providing stage entrances and providing division walls between the several auditoriums, said stage being mounted to be 25 revolute so that any part of said stage may be brought before any selected proscenium opening. 30
5. A theater structure that embodies a central stage enclosing wall with a plurality of proscenium openings through it, a plurality of separate auditoriums collectively surrounding the stage at the level of the stage openings, walled passageways located between the several auditoriums and leading 35 to the stage space to provide stage entrances and also to provide division walls between the several auditoriums, a vertically movable and rotatable stage within the central circular wall, such stage being vertically movable to the level of the proscenium openings 40 from the level of the proscenium openings to a level below, and working rooms surrounding the stage at the lower level. 45
6. A theater structure that embodies a central stage enclosing wall with a plurality of proscenium openings through it, a plurality of separate auditoriums collectively surrounding the stage at the level of the proscenium openings, walled passageways located between the several auditoriums and leading 50 to the stage space to provide stage entrances and also to provide division walls between the several auditoriums, a vertically movable and rotatable stage within the central circular wall, such stage being vertically 55 movable from the level of the proscenium openings to a level below, working rooms surrounding the stage at the lower level, and communication between the working rooms and said stage entrances. 60
- 65 7. A theater structure that embodies a cen- tral stage enclosing wall with a plurality of proscenium openings through it, a plurality of separate auditoriums collectively surrounding the stage at the level of the proscenium openings, walled passageways located between the several auditoriums and leading to the stage space to provide stage entrances and also to provide division walls between the several auditoriums, a vertically movable and rotatable stage within the central circular wall, such stage being vertically 70 movable from the level of the proscenium openings to a level below, working rooms surrounding the stage space at the lower level, and communications between the working rooms and said stage entrances. 75
8. A theater structure that embodies a central stage enclosing wall with a plurality of proscenium openings through it, a plurality of separate auditoriums collectively surrounding the stage at the level of the proscenium openings, walled passageways located between the several auditoriums and leading to the stage space to provide stage entrances and also to provide division walls between the several auditoriums, a vertically movable and rotatable stage within the central circular wall, such stage being vertically movable from the level of the proscenium openings to a level below, working rooms surrounding the stage space at the lower level, an entrance foyer completely surrounding the said working rooms substantially at said lower level, and communications between the entrance foyer and the several auditoriums. 80
9. A theater structure that involves a central revolving stage, a central revolving rigging structure above the central stage, and a structure surrounding the stage with a plurality of auditoriums facing the central stage and arranged around it. 90
10. A theater structure that embodies a central wall with a plurality of proscenium openings through it, a stage enclosed by said wall, a plurality of auditoriums facing said central stage, an auditorium at each proscenium opening, and walled passage-ways leading between the several auditoriums to the stage, providing stage entrances and providing division walls between the several auditoriums. 110
11. A theater structure that involves a central stage space enclosing wall with a plurality of proscenium openings through it, auditoriums at one level around the stage enclosing wall, work rooms around the stage space at another level, and a vertically mov- 115
- 120
- 125
- 130

able and revoluble stage in the stage space, movable between the auditorium and work room levels and rotatable to bring any part of the stage opposite any selected pro-

scenium opening.

12. A theater structure that involves a plurality of wall separated auditoriums arranged about a central stage space, with a proscenium opening from each auditorium

into the stage space, and a central stage in 10 said space revoluble to bring any part of the stage before any selected proscenium opening.

In witness that I claim the foregoing I have hereunto subscribed my name this 10th 15 day of July, 1922.

LLOYD BROWN.
